UNITED STATES PATENT OFFICE.

TEMISTOCK PEDRINI, OF NEW YORK, N. Y.

DESIGN FOR A HAT-BRUSH.

SPECIFICATION forming part of Design No. 35,129, dated September 24, 1901.

Application filed August 30, 1901. Serial No. 73,876. Term of patent 14 years.

To all whom it may concern:

Be it known that I, TEMISTOCK PEDRINI, a subject of the King of Italy, (who has resided in the United States more than five years and 5 who intends to become a citizen of the United States,) residing at New York, in the county of New York and State of New York, have invented and produced a new and useful original Design for Hat-Brushes, of which 10 the following is a specification.

My invention relates to a new and original design for hat-brushes, and is shown in the accompanying drawings, in which—

Figure 1 is a plan view of the back of the 15 brush; Fig. 2, an elevation of the brush, and Fig. 3 a cross-sectional view taken through the head of the brush on the line 3 3 of Fig. 1.

The leading features of my design reside in a hat-brush the back of which comprises a narrow and deeply and gracefully curved head, to which the bristles are secured and which is of uniform width from its crown to the point of juncture with the handle, as particularly shown in Fig. 1 of the drawings, and 25 said head provided with a central plain or flat facet and a continuous surrounding facet running at an angle to the central facet, which central and surrounding facets gradually merge into the handle of the brush, said 30 handle projecting at an obtuse angle from its point of juncture with the head of the brush.

In the said drawings the reference-numeral 1 denotes the brush, the back of which comprises a narrow and deeply and gracefully curved head 2, to which the bristles 3 are secured. The head 2 is, as shown, of uniform narrow width from its crown 4 to the point 5 of its juncture with the handle 6. The head is provided with a central plain or flat facet 7 and a continuous surrounding facet 8, running at an angle to the central facet 7. The 35 said central and surrounding facets gradually merge into the handle 6 of the brush, which handle projects at an obtuse angle 40 from the point of juncture with the head of 45 the brush.

My design presents a hat-brush of novel, distinguished, graceful, and pleasing appearance.

Having thus described my invention, what 50 I claim is—

The design for a hat-brush substantially as herein shown and described.

In testimony whereof I have hereunto set my hand in presence of two subscribing witnesses. 55

TEMISTOCK PEDRINI.
